UNITED STATES PATENT OFFICE

FRED M. POE, OF SUFFERN, NEW YORK, ASSIGNOR TO THE AMERICAN BRAKE SHOE AND FOUNDRY COMPANY, OF WILMINGTON, DELAWARE, A CORPORATION OF DELAWARE

CASTING MOLD

Application filed April 29, 1932. Serial No. 608,171.

This invention relates to molds for casting metal articles and more particularly to permanent or semi-permanent molds for repetition casting operations.

The object of the invention is to enable the use of molds for repetition casting operations and to avoid or to materially reduce the chilling effect of a casting mold upon the casting, and thereby eliminate the necessity for normalizing or annealing certain types and classes of castings, by making the walls of the mold cavity sufficiently refractory for the purpose and in such a way that they will stand the heat changes, the ordinary molding practices and other factors which tend to seriously damage and destroy refractory surfaces so that the mold cavity, made in whole or in part of refractory wall surfaces, may be used for repetition casting operations.

Heretofore it has been proposed to apply a coating of refractory material to the walls of the mold cavity; to make up the walls of a plurality of blocks of refractory material; or to inset blocks of refractory material in the metal walls of the mold cavity. The refractory material in all such cases is liable to damage and destruction because of heat changes, molding practices and other factors which enter into molding operations. I have found that the life of the refractory material may be greatly prolonged if the body thereof is reenforced and protected interiorly by metal projections which may be conveniently made in thin strips in the form of a grate of general honeycomb design, the refractory material filling the recesses between the strips and being finished off flush therewith to form the surface of the mold cavity wall. The refractory prevents or materially reduces the chilling effect of the metal mold and at the same time it is protected by the embedded grate against the ill effects of heat changes, molding practices and other factors common in casting operations, so that the life of the refractory will be prolonged to permit the mold to be continued in use for repetition molding operations.

And a further object of the invention is to

provide a mold cavity wall consisting of refractory material divided into many small independent sections, each section being surrounded by a thin metal strip which supports, reenforces and protects the refractory section against damage in molding operations.

In the accompanying drawing illustrating selected embodiments of the invention

Fig. 1 is a longitudinal sectional view of a mold.

Figs. 2 and 3 are transverse sectional views on the lines 2-2 and 3-3 respectively of Fig. 1.

Fig. 4 is a detail sectional view on the line 4-4 of Fig. 1.

Figs. 5 and 6 are detail views showing other embodiments of the invention.

Referring to the drawing, the mold comprises a drag 6 and a cope 7 having a mold cavity 8, a pouring gate 9 and a riser 10. The drag is provided with ears 11 and pins 11' thereon to engage openings 12 in the ears on the cope to register the cope in place on the drag. I have shown a mold of simple construction to illustrate the invention but I desire it to be understood that the invention may be embodied in molds of any construction and for any purpose for which it is or may be adapted. All or a part of the walls of the mold cavity are formed in part of metal and in part of refractory material, the metal and refractory material being divided and spaced and arranged so that there is a predetermined distribution of the metal in the refractory, the area and depth of the refractory being determined by the character of the casting operation to provide the proper protection for the casting and prevent the casting from becoming chilled by the metal of the mold and so that the mold can be used for repetition casting operations; and the metal being distributed and arranged in a predetermined manner to form a substantial support for the refractory and thereby provide stable surfaces for the walls of the mold cavity to enable repetition casting. These surfaces may be all refractory or they may be mainly refractory with strips or streaks of metal distributed therein. These strips or

streaks of metal are so narrow and of such small area that they will not produce a material chilling effect upon the casting or otherwise destroy the effect of the refractory.

5 The walls of the metal drag and cope are cored, bored or otherwise recessed to provide a plurality of strips 13 which extend to or almost to the surface of the mold cavity. These strips are narrow, they may be made 10 of any height and thickness and shape, and they may be arranged in any manner suitable for the purpose. In Figs. 1 to 4 I have shown the strips arranged in a symmetrical criss-cross grate providing rectangular recesses but I may provide a grate 14 with hexagonal recesses, Fig. 5, or a grate 15 with circular recesses, Fig. 6, or I may make the grate in any other general honeycomb design. The recesses of the grate are filled 15 with refractory material 16 of any suitable kind and this refractory material is preferably finished off flush with the outer edge of the grate. The refractory material may be packed in the recesses of the mold cavity 20 walls in any suitable manner and by any suitable means. The bottom wall of the mold pouring gate including the end wall of the mold cavity may be recessed to provide studs 17 in a steplike arrangement with the 25 intervening recesses filled with refractory material 18, and the bottom wall of the riser, Fig. 2, may be similarly provided with studs 19 and refractory material 20. Instead of coring or boring the walls of the mold cavity 30 to provide the grate for the refractory, the grate may be provided in any suitable manner, the only requirement being that it shall have sufficient rigidity and that it shall be secured in place in the mold to hold and support the refractory and provide a mold cavity wall suitable for the purpose. As before 35 stated, the grate may be in any form of honeycomb design suitable to receive the refractory material and to constitute a support 40 and protection therefor without to any material extent chilling the casting. While the aggregate area of the grate exposed at the surface of the wall may be sufficient if combined in a solid section to chill a casting at 45 the contact therewith, the distribution of this metal in the form of a grate composed of narrow strips avoids any material chilling effect therefrom and at the same time the grate provides a substantial support for the 50 refractory to protect the refractory against damage in the casting operations and enables the mold to be used for repetition casting for a long time. For the reason that the grate 55 does not have any material chilling effect upon the casting, I prefer to finish off the refractory flush with the grate but there may be conditions for which it is desirable to provide a continuous refractory surface for 60 the wall of the mold cavity and in such case 65

the refractory may be finished off over the grate.

Preliminary to the casting operation I prefer to coat the surface of the mold cavity walls with lamp black or any other protective coating which is or may be suitable for the purpose. I do not restrict the invention to refractory material of any particular kind but I may use any material of low heat conductivity suitable for the purpose; 75 and it is my intention to vary the honeycomb design of the grate as may be best for particular molds but in all cases the refractory material will be divided into separate and independent sections and each section 80 will be reenforced and protected by the grate. Casting operations are more or less rough and there is always the liability of some heavy article falling on the cavity wall in the cope or drag and damaging the refractory material, and if this refractory forms a continuous surface the damage may be spread over such an area that complete renewal of the refractory is necessary; but with my invention such damage will usually 85 be confined to the immediate section or sections receiving the damaging blow because each section is independently supported and protected by the grate and damage to one section of refractory material is not 90 likely to spread to other sections. Therefore the maintenance cost of a repetition mold having refractory cavity walls is materially reduced by my invention and interruption of the use of the mold for 95 repairs is correspondingly reduced.

I do not limit the invention to the particular form, construction or arrangement shown and described herein but I reserve the right to embody the invention in any 100 mold and in any form, construction and arrangement suitable for the purpose and within the scope of the following claims.

I claim:

1. A wall with which the molten metal contacts in a mold and comprising refractory material and a metal grate embedded in the refractory material to support and protect the refractory material. 110
2. A wall with which the molten metal contacts in a mold and comprising refractory material and a metal grate of honeycomb design embedded in the refractory material to support and protect the refractory material. 115
3. A wall with which the molten metal contacts in a mold and comprising refractory material and a metal grate having independent recesses therein and embedded in the refractory material, the said refractory material filling the recess and being divided into independent sections by the grate. 120
4. A wall with which the molten metal contacts in a mold and comprising refractory material and a metal grate embedded therein 125

and having rectangular recesses which divide the refractory material into separate rectangular sections.

5. A wall with which the molten metal contacts in a mold and comprising refractory material and a metal grate embedded therein and having hexagonal recesses which divide the refractory material into separate hexagonal sections.
